UNITED STATES PATENT OFFICE

115,614

DESIGN FOR A LAVATORY UNIT

Paul Ebling, Minneapolis, Minn., assignor to The Showerway Company, Minneapolis, Minn., a corporation of Minnesota

Application April 27, 1939, Serial No. 84,599

Term of patent 14 years

To all whom it may concern:

Be it known that I, Paul Ebling, a citizen of the United States and residing in the city of Minneapolis, county of Hennepin, and State of Minnesota, have invented a new, original, and ornamental Design for a Lavatory Unit, of which the following is a specification, reference being had to the accompanying drawing, forming a part thereof, wherein,

Fig. 1 is a front perspective view of a lavatory unit showing my new design, and

Fig. 2 is a top plan view of the same.

I claim:

The ornamental design for a lavatory unit, as shown.

PAUL EBLING.
